UNITED STATES PATENT OFFICE.

JOHN F. RAYNOLDS, OF MINNEAPOLIS, MINNESOTA, ASSIGNOR TO THE PARAFLECTOR COMPANY, OF MINNEAPOLIS, MINNESOTA, A CORPORATION OF DELAWARE.

HEADLIGHT REFLECTOR.

Application filed April 27, 1925. Serial No. 26,105.

This invention has for its main object the projection of a beam of light for use in motor vehicle head lamps and the like, having a more desirable shape, and with better 5 distribution of candle-power or light intensities than is afforded by the various devices now in use.

The invention consists generally in the construction and arrangement of parts forming 10 a reflector as hereinafter described and particularly pointed out in the claims.

In the accompanying drawings forming part of this specification,

Figure 1 illustrates a front elevation of a 15 reflector having its surface divided into strips by means of circular arcs; lines 1—1 etc. indicating the planes in which the light is spread from various points on a single strip;

Figure 2 is a horizontal sectional view on the line 2—2 of Figure 1 showing a reflector of preferred form, comprising a plurality of flat strips arranged to produce the desired spread of the reflected light rays;

Figure 3 is a diagrammatic view illustrating a cross section of a light beam from two headlamps arranged as on a motor vehicle, to show the particular form of beam structure which it is desired to produce for 30 illuminating the roadway ahead of said vehicle;

Figure 4 illustrates a front elevation of a single strip formed from a circular parabolic reflecting surface as shown in Figure 35 2; b—b' being a transverse element lying in plane P at its intersection with strip S;

Figure 5 illustrates a side elevation of the strip shown in Figure 4, showing its curvature in a vertical plane parallel to the principal axis of the reflector.

Figure 6 illustrates an enlarged cross sectional view in plane P (Figure 4), showing various curvatures into which the transverse element of the strip may be formed to give a desired amount of spread or divergence to the reflected rays.

Figures 7 and 8 are modifications showing reflectors having differently designed curvatures of reflecting strips to produce varying 50 amounts of divergence to the rays striking said strips;

Figure 9 illustrates a front elevation of a modified form of reflector showing the strips arranged in non-circular continuous curves,

identical in curvature and symmetrically arranged with respect to the vertical meridian V—V; and

Figure 10 illustrates a method of laying out the surface of a reflector (or die) into strips, using circular arcs.

It is well recognized by illuminating engineers that the light beam projected from the headlamps of motor vehicles should have a pattern in cross section similar to that shown in Figure 3 and that the distribution 65 of light intensities within such a beam should be substantially as shown by the lines of equal intensity in Figure 3.

The figures merely indicate the comparative candle powers in a suitable beam projected from two lamps, when correctly adjusted as on a motor vehicle and readings made at 100 feet. This beam resembles one-half of an ellipse, divided on its major axis, the whole axes preferably having a ratio of 75 about 1.8 to 1.

The commonest form of reflector used in motor vehicle headlamps is a circular parabolic reflector of about 1 1/4" focal length (paraboloid of revolution). There are also 80 a number of patented reflectors having an unbroken reflecting surface but which are non-circular in sections transverse to the principal axis, being so designed according to a certain plan or theory, which causes the 85 light rays to be projected in lines which deviate from parallelism by an amount measurably greater than in the case of the above-mentioned circular parabolic reflector—the source of light being considered the same 90 and adjusted for least divergence of the rays.

The improvement disclosed herewith is distinctly applicable to both classes of reflector, above mentioned, and whether they 95 are designed with a single focal point as in the Lester Patent No. 1,417,926 or with a plurality of such points. More particularly, however, I desire to apply this improvement to the second class of non-circular reflectors 100 whether stygmaic or astygmaic in design, in combination herewith to produce a beam which exceeds the requirements of the various State laws, and produce a more satisfactory illumination of the roadway ahead of 105 the vehicle with a minimum of glaring rays. This is not realized by spreading the light rays in one plane or in several planes. They

must be spread in continuously changing planes depending upon the point on the reflecting surface which is under consideration.

By constructing the reflector with a plurality of strips 11, (as shown in Figures 1 and 2) whose edges are continuous curved lines if projected on the plane of the reflector's mouth perpendicular to the principal axis; and by the use of suitably curved cross sections or transverse elements, for symmetrically located strips, the most desirable and efficient distribution of light may be secured in a beam of correct cross-section or pattern. Instead of spreading the rays horizontally (in one plane), thus producing a band of light with highest intensity near its horizontal center line; the distance and direction of travel of the various rays are considered, and the reflecting surface made to direct the proper amount of light to each portion of the lighted field which is assumed to be a level, slightly crowned highway.

My invention consists of a broken, divided or configurated reflecting surface, originally either paraboloidal in shape or modified as above mentioned, said surface being divided into two series of strips, which are symmetrically arranged about the vertical meridian V—V of the reflector. The bounding edges of these strips are continuously curved lines or circular arcs when projected on a plane perpendicular to the main axis of the reflector (plane of reflector mouth opening) having their convex sides toward the vertical meridian of the reflector. Broken lines 1—1, 2—2, etc., in Figure 1, show the planes in which light is spread from points on various transverse elements of a single strip. The surface of the strips at such transverse elements is made to assume a curvature less marked than that of the original smooth surface or it may be made flat or plane, or may have a curvature opposite to that of the original reflector surface, i. e. convex with relation to the main reflector axis (Figure 8). Furthermore the radius of curvature of a strip at any such transverse element may be greater near one edge than the other so as to produce greater deviation of the rays in one direction in the spreading plane than in the other. With this method or combination of methods practically any desired alteration may be effected in a beam from a reflector as described above, and the distribution of light within the projected beam may be arranged to best meet the requirements of State laws and actual conditions of service. No diffusing or refracting "lens" is necessary, only a piece of clear sheet glass as a cover in the lamp door is required. Loss of light by absorption and diffusion is diminished.

The light is concentrated to a proper extent, in the upper central portion of the beam (Figure 3), thus illuminating more distant

points on the roadway and producing less apparent change in illumination to the operator's eye as it is directed along the lighted path.

Referring to Figure 4, the transverse element $b-b'$ originally had a smaller radius of curvature as a part of the unbroken circular parabolic surface before this surface was divided into strips and reformed, as shown at $a-a'$, Figure 6. Line T—T' is tangent to the curved edge of the strip at b' . Now in Figure 5, the inclination of plane P to the horizontal is fixed by its construction perpendicular to the tangent T—T'. Plane P contains the transverse element $b-b'$, also its radius of curvature which is centered at o' , in Figure 6. This figure shows an enlarged view in plane P of the transverse element $b-b'$ and also shows the original curvature of this element at $a-a'$, with radius centered at O, together with $c-c'$ a straight line or flat transverse element with radius of curvature infinite, and $d-d'$ having its center of curvature on the opposite side of the strip.

The preferred embodiment consists of a reflecting surface divided into strips whose edges are concentric circular arcs when projected on the plane of the reflector mouth opening. Figure 10 illustrates how these arcs may be constructed. In this case a single base line perpendicular to the vertical meridian plane of the reflector is used. The centers of the two series of arcs are located on this line equidistant from the meridian plane. The radius arm 12 is adapted to slide vertically on the upright post or rod 13, so as to preserve the same radius throughout a given arc.

Where arcs of equal radius are used as illustrated in Figure 9, the scribing point on arm 12 retains the same radius or distance from post 13, while post 13 is moved away from or toward the vertical meridian plane of the reflector die, in order to describe circular arcs of equal radii on the surface of the die.

I claim as my invention:

1. A concave reflector having its surface divided into two series of strips or zones; each strip being formed so that its mean radius of curvature, in the plane containing a transverse element of said strip, is greater than the mean radius of curvature of the same section of the original surface; said strips or zones arranged symmetrically with respect to the vertical meridian of said reflector and having their edges in curved lines on the reflector surface, the projections of said lines on a plane perpendicular to the main axis of said reflector forming two series of concentric circular arcs having their centers on opposite sides of the projected vertical meridian, equidistant from it and below the horizontal axial plane, said arcs lying be-

tween the projected vertical meridian and their respective centers.

2. A concave reflector having its surface divided into two series of strips or zones; 5 each strip being formed so that its mean radius of curvature, in the plane containing a transverse element of said strip, is greater than the mean radius of curvature of the same section of the original surface; said 10 strips or zones arranged symmetrically with respect to the vertical meridian of said reflector and having their edges in curved lines on

the reflector surface, the projections of said lines on a plane perpendicular to the main axis of said reflector forming two series of 15 circular arcs of equal radii and having their centers on opposite sides of the projected vertical meridian and below the horizontal axial plane of said reflector, said arcs lying between the projected vertical meridian and 20 their respective centers.

In witness whereof, I have hereunto set my hand this 14th day of April, 1925.

JOHN F. RAYNOLDS.
